[57] CLAIM

The ornamental design for an insulated flask, as shown and described.

DESCRIPTION

FIG. 1 is a front elevational view of an insulated flask showing my new design;

FIG. 2 is a right side elevational view thereof, the left side elevational view is a mirror image;

FIG. 3 is a rear elevational view thereof;

FIG. 4 is a top plan view thereof;

FIG. 5 is a bottom plan view thereof;

FIG. 6 is a partial cross-sectional view thereof taken on line 6—6 of FIG. 4 with the stopper or plug shown in full side elevation and the insulating glass liner and associated seals removed for clarity of illustration;

FIG. 7 is a rear elevational view of a modification of my new design showing the stopper or plug with two handles instead of one; and

FIG. 8 is a top plan view of FIG. 7, it being understood that the remaining views of the modified design not shown are similar to those in FIGS. 1-6.

FIG. 2.

FIG. 1.

FIG. 4.

FIG. 3.

FIG. 6.

FIG. 5.

FIG. 8.

FIG. 7.
